Design No. 12,699, dated January 17, 1882.

UNITED STATES PATENT OFFICE.

LE ROY W. FAIRCHILD, OF NEW YORK, N. Y.

DESIGN FOR A PENCIL-CASE.

SPECIFICATION forming part of Design No. 12,699, dated January 17, 1882.

Application filed April 5, 1881. Term of patent 7 years.

To all whom it may concern:

Be it known that I, LE ROY W. FAIRCHILD, of the city, county, and State of New York, have invented or produced a new and original 5 Design for Cases for Pencils and similar Implements, designed to be worn as an amulet or charm, of which the following is a clear, full, and exact description, reference being had to the accompanying photographic illustration, 10 forming part thereof.

The accompanying illustration represents a side elevation of my design as a whole, in which A indicates the body of the tubular case. Upon the side of this case A, I affix a raised figure 15 of an anchor, B, through the eye of which an imitation cord, rope, or line, C, is passed, and which is wound around the body of the anchor and then under one of its flukes, as shown.

The terminal portions D of the case A may 20 be left plain, as shown in the illustration, or they may be provided with ornaments of any desired or suitable character, as may be preferred, and in like manner the position or winding of the cord or line C may be varied without materially altering the design, which consists of the case A with the anchor B applied thereto.

The case and the anchor and line may be shown in metals of different kinds or colors, or in different shades of the same metal, in order 25 to produce a more striking effect and render the design as a whole more ornamental.

What I claim is—

The herein-described design for a case for pencils and similar implements, consisting of 30 the case or body A and the anchor B applied thereto, substantially as shown.

LE ROY W. FAIRCHILD.
